UNITED STATES PATENT OFFICE.

JAMES H. GILSON, OF OMAHA, NEBRASKA.

HELMET.

Application filed October 23, 1920. Serial No. 419,003.

To all whom it may concern:

Be it known that I, JAMES H. GILSON, a citizen of the United States, residing in the city of Omaha, in the county of Douglas and 5 State of Nebraska, have invented certain new and useful Improvements in a Helmet, and have described the same in the following specification, illustrated by the accompanying drawings.

10 My invention relates to a covering for training the hair on a human head to stand and lie habitually in a desired position, as in the styles known as pompadour, parted, or bobbed. It comprises an adjustable cover, 15 encircling the wearer's head and adapted to hold the hair in place, especially by night, and especially when wet and drying. Among the objects of my invention are to render the helmet easily adjustable to heads of even 20 widely different sizes without impairing its efficiency in any such adjustment; to make the same well ventilated and comfortable to wear; to promote the drying of the hair therein, when wet, by adapting one portion 25 of the helmet to permit the escape of moisture by evaporation, and another portion thereof to extract moisture therefrom by absorption; to hold the same securely and comfortable in position hugging the wearer's 30 head, especially during his sleeping hours; to provide an improved helmet capable of general application and use as a head covering; to prevent the hugging portion of the helmet from slipping on the head; and such 35 further objects, advantages and capabilities as will later more fully appear. To accomplish these results, I incorporate in my improved helmet, as parts thereof, a crown covering which is of fine netting or other porous 40 material and of special construction, a rough and moisture-absorbing cushion therein, and a pair of elastic straps of adjustable length, which are applied to the covering.

45 While my helmet is more particularly described in connection with training the hair, I wish it to be understood that the same is of value as a head covering for other and more general purposes and can be made either with a top covering of open work material 50 for ventilating and drying purposes, or of knitted material, ordinary cloth, or imperforate material should the helmet be desired for general use other than training the hair.

55 My invention further resides in the combination, construction and arrangement of parts illustrated in the accompanying draw-

ings, and while I have shown therein a preferred embodiment, I desire the same to be understood as illustrative only, and not as limiting my invention.

60 In the drawings:

Fig. 1 is a perspective view of a hair helmet which is constructed in accordance with these principles and is seen from behind. Fig. 2 is a like view of the same helmet in 65 operative position on the wearer's head, as seen from one side. Fig. 3 is a like view of the same specimen of the invention, as adjusted in use and seen from in front.

70 The crown covering of this illustrative specimen of the invention is denoted in these views by the numeral 4. It is composed of porous fabric, and has, when in use, the general shape of a hollow hemisphere. Being 75 slitted from the middle to the periphery on a meridian line, it is adjustable to an increased circumference by opening apart the edges 5 of the slit, as in Fig. 1, or to a smaller size by drawing these edges overlappingly together, as may be required by the size of 80 the head to which the helmet is applied. It has a binding tape 6 which hems these edges of the slit. It has a pair of elastics 7 and 7', of adjustable length, which are attached internally to the covering at the edges 5 respectively, and provided with the sliding loops 8 to engage the hooks or catches 9 at the front margin of the covering. It has 85 also the spaced slits, or eyes, 10, which accommodate the elastic 7', running therein, 90 alternatively according to the size to which the helmet is adjusted.

95 The cushion 11, forming part of the helmet, is a broad band of felt, or other spongy material, lining the margin of the covering 4. Being pervious to water, it is adapted, unlike the sweat-band of a hat or cap, to abstract moisture by absorption from the hair of the head to which it is applied; and, being both thick and soft, is adapted to hold 100 its position on the head without slipping, and without discomfort to the wearer. Or if desired this band 6 may be of material impervious to water. Should the crown covering be formed of knitted material or the 105 like the cushion 11 could be omitted.

110 In using this helmet, the wearer first combs his hair, either wet or dry as the case may be, in the desired style and position. Then with the helmet wide open behind, as in Fig. 1, and without disturbing the position of the hair, he carefully lowers the cov-

ering over the top of the head to a position overlapping a portion of his forehead and completely underlapping and covering its occipital point, as plainly indicated in Fig.

5 2. Then he closes the covering, and brings its edges 5 to a mutually contacting or overlapping position back of the head, by drawing the elastics forward, and by attaching them terminally, under comfortable tension, 10 to the front of the helmet by the loops and catches 8 and 9.

Then, sleeping or waking, as the case may be, he wears the helmet for a time in the described position, and thereby holds and 15 trains the hair which is therein. Then, after loosening the elastics, he lifts off the helmet without disturbing the adjustment of the hair; and all this he may repeat as often as the hair needs further training. In this way 20 the several above specified objects of the invention are successfully accomplished. Or if used for general purposes as a head covering the helmet will function in an obvious manner.

25 I claim as my invention—

1. A hair helmet comprising a crown covering formed of porous material and having a slit from the periphery toward the middle of the covering, an absorbent cushion lining 30 the peripheral margin of the covering, and elastic means for closing the slit and causing the cushion to hug the wearer's head.

2. A hair helmet comprising a crown covering having a marginal slit behind and 35 adapted to overlap a portion of the wearer's forehead and to underlap the occipital point of his head, a spongy cushion lining the peripheral margin of the covering, and a pair of elastics of adjustable length, attached to 40 opposite sides of the slit respectively and adapted to hug the cushion to the head.

3. A helmet comprising a crown covering formed of porous material and having means for permitting expansive movement 45 thereof when being removed from the head, a cushion lining the peripheral margin of the covering, and elastic means for closing said first mentioned means and causing the cushion to hug the wearer's head.

50 4. A head covering comprising a crown portion having means to permit expansion and contraction thereof to facilitate easy application to and removal of the same from the head of the wearer, a marginal edge portion adapted to be drawn into snug engagement with the head, a pair of elongated elastic elements secured to said marginal edge portion and arranged to be drawn in opposite directions around the head, coacting

means on said elastic elements and said marginal edge portion to secure said elements to said covering with the marginal edge hugging the wearer's head. 60

5. A head covering comprising a crown portion having means to permit expansion 65 and contraction thereof to facilitate easy application and removal of the same to and from the head of the wearer, a marginal edge portion adapted to be drawn into snug engagement with the head, a pair of elongated 70 elastic elements secured to said marginal edge portion and arranged to be drawn in opposite directions around the head, coacting means on said elastic elements and said marginal edge portion to secure said elements to 75 said covering with the marginal edge hugging the wearer's head, and means for adjusting the length of said elastic elements.

6. A head covering comprising a crown portion having expansible means to permit 80 expansion and contraction thereof to facilitate easy application to and removal of the same from the head of the wearer, a marginal edge portion adapted to be drawn into snug engagement with the head, a pair of 85 elongated elastic elements secured to the opposite sides of said expansible means, an opening in said crown portion adjacent the point of attachment of one of said elastic elements whereby the other elastic element 90 may pass therethrough and said pair of elastic elements be drawn in opposite directions around the head, and means for securing said elements in drawn position with the marginal edge hugging the wearer's head. 95

7. A head covering comprising a crown portion having expansible means at one side thereof to permit expansion and contraction to facilitate easy application to and removal from the wearer's head, a marginal edge portion adapted to be drawn into snug engagement with the head, an elongated elastic element secured to the outer end of each of the sides of said expansible means, said elastic elements being adapted to be drawn in opposite directions around the head, means for securing the elastic elements in drawn position with the marginal edge hugging the wearer's head, the sides of said expansible means being free of any projections or fastening elements except where said elastic elements are secured whereby said sides are free to slide with relation to each other to permit free expansion and contraction of the crown portion. 100

Witness my signature at Omaha, Nebraska, October 19, 1920.

JAMES H. GILSON.
